KNIFE SHARPENER

Alfred W. Madl, Mequon, Wis., assignor to John Oster
Manufacturing Co., Milwaukee, Wis., a corporation of
Wisconsin

Filed Apr. 4, 1963, Ser. No. 74,305

Term of patent 14 years

(Cl. D37—1)

FIG. 1 is a front perspective view of a knife sharpener embodying my design;

FIG. 2 is an enlarged right side elevational view thereof;

FIG. 3 is an enlarged top plan view thereof;

FIG. 4 is an enlarged rear elevational view thereof;

FIG. 5 is an enlarged fragmentary sectional view taken along line 5—5 of FIG. 1; and

FIG. 6 is an enlarged fragmentary sectional view taken along line 6—6 of FIG. 3.

I claim:

The ornamental design for a knife sharpener, as shown.
